UNITED STATES PATENT OFFICE.

GEORGE W. ANSLEY AND JOSEPH H. BOYD, OF MEDICAL LAKE, WASHINGTON;
SAID BOYD ASSIGNOR TO SAID ANSLEY.

CLOTHES-DRIER.

SPECIFICATION forming part of Letters Patent No. 447,551, dated March 3, 1891.

Application filed November 21, 1890. Serial No. 372,212. (No model.)

To all whom it may concern:

Be it known that we, GEORGE W. ANSLEY and JOSEPH H. BOYD, citizens of the United States, residing at Medical Lake, in the county 5 of Spokane and State of Washington, have invented certain new and useful Improvements in Clothes-Driers; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to certain new and useful improvements in clothes-racks of that class wherein the arms are adapted to be folded out of the way when not in use; and it has for its objects, among others, to provide an improved device of this character 20 wherein the arms may be inclosed within a suitable case or pocket when not in use, the support being provided with a swinging bail or handle, which serves also as a support for 25 the arms when the latter, or any one of them, are in use.

Other objects and advantages of the invention will hereinafter appear, and the novel features thereof will be specifically defined 30 by the appended claim.

The novelty resides in the peculiarities of construction and the combinations, arrangement, and adaptation of parts, all as more 35 fully hereinafter described, shown in the drawings, and then particularly pointed out in the claim.

The invention is clearly illustrated in the accompanying drawings, which, with the letters of reference marked thereon, form a part 40 of this specification, and in which—

Figure 1 is a perspective view of our improved clothes-rack. Fig. 2 is a vertical section through the same. Fig. 3 is a top plan with a portion of the arms extended.

45 Like letters of reference indicate like parts throughout the several views.

Referring now to the details of the drawings by letter, A designates a suitable back plate or support, to which is secured the casing 50 B, preferably semi-cylindrical and of

metal, with a bottom a of any suitable material, the back plate being formed or provided with a lug b at its upper end, which is provided with a key-hole slot or opening c, to engage suitable means, as a screw or nail, by 55 which the device may be removably suspended in any desired place.

C is the top to the casing, which is provided around its edge with a plurality of openings d, which also extend for a short distance 60 through the upper portion of the vertical flange of the top C, forming shoulders e, on which the supporting-arms may find a bearing when extended.

The arms D are loosely confined within the 65 casing, and at their inner ends are provided each with a cross-pin f or other suitable provision to prevent their being entirely withdrawn from the chamber formed by the casing and back plate and yet allow them to be 70 moved freely within the same. The outer ends of the arms upon their under face are provided with eyes or hooks or other analogous provisions g, which may serve to hook things onto when the arms are extended. 75

F is a bail pivotally connected to the casing, and serves as a means for carrying the clothes-rack from place to place when necessary, and when in use this bail is thrown down into a horizontal position, as shown, 80 where it rests upon a lug h on the upper end of the casing, and serves to receive the supporting-arms.

The operation is simple and will be readily understood. When any one or all of the 85 arms are to be used, they are drawn up vertically until the same have been removed to their fullest extent, when, by bringing them into a horizontal position, they will be there retained by reason of their engagement upon 90 the shoulder, the bail, and upon the under side of the top of the casing.

The device is light, compact, not liable to get out of order, and in use has proved very efficient. 95

What we claim as new is—

The clothes-rack described, consisting of the back plate, the casing secured thereto and provided with a bottom, and a top provided with openings at its outer edge, forming 100

shoulders, the swinging bail having its ends extended inward horizontally and forming the pivots on which it turns, the lug therefor attached to the vertical flange of the top, and 5 the supporting-arms free to be moved within the casing and at their outer ends provided with eyes or loops, substantially as specified.

In testimony whereof we affix our signatures in presence of two witnesses.

GEORGE W. ANSLEY.
J. H. BOYD.
